COMBINED BENCH, VANITY DESK AND CHEST UNIT

Merton L. Gershun, Miami Beach, Fla., assignor to American Furniture Co., Inc., Martinsville, Va., a corporation of Virginia

Filed May 13, 1960, Ser. No. 60,578

Term of patent 7 years

(Cl. D33—7)

FIG. 1

FIG. 2

Figure 1 is a perspective view of a combined bench, vanity desk and chest unit embodying my new design;

I claim:

The ornamental design for a combined bench, vanity desk and chest unit, substantially as shown and described.
